MERCHANDISING CONTAINER OR THE LIKE

Peter A. Latham, Stow, and Paul E. Brefka, Framingham, Mass., assignors, by mesne assignments, to Socony Mobil Oil Company, Inc., New York, N.Y., a corporation of New York

Filed Dec. 31, 1964, Ser. No. 83,248

Term of patent 14 years

(Cl. D58—12)

FIG. 1 is a front perspective view of a merchandising container or the like showing our new design; and

FIG. 2 is a rear perspective view thereof.

The dominant features of our design reside in the portion shown in full lines.

We claim:

The ornamental design for a merchandising container or the like, substantially as shown and described.
